UNITED STATES PATENT OFFICE.

OSCAR S. LESLIE, OF MILWAUKEE, WISCONSIN, ASSIGNOR OF ONE-HALF TO
HENRY LANDT, OF SAME PLACE.

SHIELD FOR POSTS.

SPECIFICATION forming part of Letters Patent No. 291,208, dated January 1, 1884.

Application filed January 26, 1883. (No model.)

To all whom it may concern:

Be it known that I, OSCAR S. LESLIE, a citizen of the United States, residing at Milwaukee, in the county of Milwaukee and State of Wisconsin, have invented certain new and useful Improvements in Shields for Posts; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 The object of my invention is to provide a device for preventing posts which are set in the ground from being disturbed by frost. It is a well-known fact that the supporting-posts of verandas and fences when set in ground which is subject to severe frosts are frequently heaved up and deranged by the action of the frost upon the surrounding earth. With my device the earth is kept from contact with the post, thereby relieving it from all liability of derangement to which it would otherwise be subjected.

My invention consists in providing a movable pipe or shield around and free from contact with the post, which shield will exclude 30 the earth and all moisture from that portion of the post which is above the lowest frost-line in the earth. This pipe or shield is free to move upward and downward, or slightly in a horizontal direction, without disturbing the post.

35 The construction of my invention is further explained by reference to the accompanying drawings, in which—

Figure 1 is a vertical section, and Fig. 2 a 40 cross-section thereof.

Like parts are represented by the same reference-letters in both views.

A represents the supporting-post, which, as shown, is made of tubing. A solid wood or 45 metallic post may, however, be substituted therefor.

B is a base or supporting block. C represents the structure to be supported.

D is the movable shield by which the frozen earth is prevented from coming in contact with 50 the post A.

E represents the earth between the surface and the lowest limit of the frost.

F are elastic rings or bearings, which are interposed between the post and shield, to prevent the action of the shield from being transmitted to the post. The bearings F are rigidly attached to the shield D by bolts a a.

G is a stationary shield or water-shed, which serves to prevent water from entering 60 the shield D. The shield G is connected with the post A by bolts b b.

H is a packing, by which water is excluded from the post A.

It is obvious that as the lower end of the 65 shield D extends below the frost-line in the earth and the upper end projects above the surface it is impossible for the upheaval of the earth around the post to affect the post, as the shield D is free to move upward and 70 downward with the frozen surface of the earth without transmitting any movement of the frost to the post A.

It is obvious that my devices may be applied to fence and other posts, the results attained or end accomplished being substantially the same.

Having thus described my invention, what I claim as new, and desire to secure by Letters Patent, is—

The combination of post A, inclosing-shield D, upper and lower packing-rings F F, interposed between said post and said shield, supporting-base B, packing H, interposed between said base and said post, water-shed G, and 85 supporting-rods b b, all substantially as and for the purpose specified.

In testimony whereof I affix my signature in presence of two witnesses.

OSCAR S. LESLIE.
